UNITED STATES PATENT OFFICE

2,384,602

MOP

Paul B. Coats, Chicago, Ill.

Application August 17, 1942, Serial No. 455,081

1 Claim. (Cl. 15—229)

This invention relates to scrubbing and cleaning devices and more particularly to mops and wringers or drainers therefor. One object is to provide a mop that may be used as a wet mop or as a dust mop and that is efficient for scrubbing, washing walls and woodwork, washing automobiles, for washing ceilings, windows and for general cleaning of a like nature. A further object is to provide a mop that when used dry will pick up lint, ashes or like material from floors, carpets, rugs, etc.

A further object is to provide a mop that is practically self-cleaning, that may be used to remove dirty water from floors after scrubbing, that may be wrung practically dry without touching the hands to the mop head, and that is durable, efficient and handy in operation.

A still further object is to provide a mop that is light in weight, strong and efficient in use, very easy to keep clean and sanitary, inexpensive to manufacture, and that is streamlined in design permitting its use readily in out-of-the-way and ordinarily inaccessible places.

A further object is to provide a mop including a drainer that is adjustable to fit pails and like containers of different sizes. With the foregoing and other objects in view the invention consists in the combination and arrangement of parts to be hereinafter fully described, pointed out in the claims and illustrated in the accompanying drawing which forms a part of this patent and in which—

Fig. 1 is a view in perspective of the mop proper, a portion of the handle being broken away.

Fig. 2 is an enlarged cross sectional view through the mop head on the line 2—2 of Fig. 1.

Fig. 3 is a fragmentary view of the mop yarn and tape for securing the same to the mop head.

Fig. 4 is a top plan view of the drainer employed.

Fig. 5 is a vertical longitudinal sectional view through the drainer taken on the line 5—5 of Fig. 4.

Fig. 6 is a transverse sectional view through the drainer on the line 6—6 of Fig. 5.

Fig. 7 is a view of the drainer in elevational perspective, and,

Fig. 8 is a view of the mop and drainer on a reduced scale, the drainer being shown applied to the rim of a pail.

Like reference characters denote corresponding parts throughout the several views.

The mop comprises a head preferably oblong and streamline in shape provided with a plurality of tufts or strands of yarn preferably arranged in

longitudinal rows; a handle for the head; and a drainer shaped to snugly receive the head with yarn and provided with drain slots to vent the water pressed from the yarn, the drainer being provided with adjustable hooks for securing it to the rims of pails of various sizes.

The elongated or oblong streamlined mop head is preferably formed with a convex top face 1 connecting the longitudinally extending parallel lateral sides 2, 3, the side 3 being somewhat wider than the side 2, and with a flat lowermost face 4 in which are formed two parallel spaced substantially U-shaped channels 5, 6 of identical structure extending from end to end of the head, said head being formed with the tapered socket 7 for the handle 8.

Received in each channel and extending transversely thereof are a plurality of closely associated strands of lint-proof mop yarn 8 preferably sewed or otherwise secured to a piece of tape 9 upon which between the strand ends is received a strip of material 10, of hardwood or the like, the assembly being securely held in place by fasteners 11 passing therethrough and into the head, the ends of the strands 8 normally extending outwardly substantially two inches from the head. In scrubbing or washing a surface the head is dipped into the water in the usual manner and the wet yarn then applied to the spot to be cleaned. With the handle removed the mop may be used for cleaning bath room fixtures and for other purposes. When the mop is dry or moist-dry it may be used for dusting, cleaning curtains and drapes, etc.

For wringing water from the mop when the yarn is saturated a wringer or drainer 12 is employed preferably formed of wood, the wringer consisting of a stout fairly thick flat sided bed 40 portion 13, the ends thereof being beveled as at 14 and 15 in opposite directions or toward each other, and the side walls 16, 17 rising upwardly from said bed forming a trough-like member open at its ends, the relatively adjacent faces of said side walls being beveled divergently from the bed, the outer faces of said walls being in the plane of the corresponding sides of the bed, or straight up from said bed. The ends of the side walls are beveled toward each other.

Extending transversely of the top face of the bed are a plurality of spaced parallel recesses 18 which at their ends extend entirely through the bed to form slots 19, one slot at each end of a recess. Registering with the several slots 19 are the vertical recesses 20 in the walls 16, 17

the upper ends of which wall recesses are spaced downwardly from the upper edges of the walls, said recesses continuing to the lower wall face and serving together with the slots 19 to drain water from the bed, from recesses 18 and from the walls. Hinged in grooves 22a in the bottom face of the bed by wire or like staples or hinges 21 are the substantially U-shaped hooks 22, 22 10 the upper ends thereof being bent reversely for engagement with the rim of a pail 23, said hooks being disposed parallel with the beveled ends of the bed. The bevel of the ends of the bed and the position of the hooks 22, 22 is to permit the application of the hooks to the circular rim of a pail as shown, the drainer being disposed inside the pail at the top thereof so that water passing through the bed slots and wall recesses will run into the pail. The hooks are adjustable in a rotary manner in their slotted bed portions to permit their attachment to pails having rims of different diameters.

When the mop yarn is saturated with water and it is desired to wring it out the mop head is disposed in the drainer while the operator bears down on the handle and imparts a slight back and forth or rocking movement to the handle so that the yarn will be pressed against the bed and squeezed and wrung out between the rails 16, 17. A very efficient wringing may be imparted to the mop yarn in this way—in fact it being almost possible to wring the same completely dry. After use the head may be cleaned perfectly by boiling in water containing a cleaning chemical or in other suitable manner.

The drainer or wringer is applied to the pail 35 with the shorter wall 17 next to the pail rim.

5 The space between the walls 16, 17 is such as to snugly receive the water-saturated mop yarn so that pressure upon and oscillation of the head will effectually squeeze the water out of the yarn against the bed and walls. It will be noted that the tape 9 and strip 10 positively secure each and every strand of yarn to the head as the strands are all sewed to the strip.

10 As many modifications of the invention will readily suggest themselves to those skilled in the art I do not limit the invention to the specific means or apparatus herein illustrated and described.

What is claimed is:

15 In a mop, an elongated streamline head having an overall smooth convex top face defined by parallel longitudinally extending lateral sides and a flat lowermost face, one of said lateral sides being wider than the other, an upwardly directed socket in said head at a point of juncture of said top face and said wide lateral side; said lowermost face being formed with two parallel channels having substantially parallel walls, strands of mop yarn taped together substantially midway between their ends, the taped portions being positioned in said channels, yarn securing means extending longitudinally of said channels and beneath said taped portions, fastening means extending through said first mentioned means and 20 said taped portions and into said head, the ends of said strands extending downwardly from said first means and forming closely associated strand portions in parallel rows extending from end to end of said head, and a handle in said socket.

PAUL B. COATS.
